UNITED STATES PATENT OFFICE.

EDWARD L. COMBES, OF MILWAUKEE, WISCONSIN.

ATTACHMENT FOR TABLES AND OTHER SUPPORTS.

1,098,482.

Specification of Letters Patent.

Patented June 2, 1914.

Application filed December 5, 1912. Serial No. 735,030.

To all whom it may concern:

Be it known that I, EDWARD L. COMBES, a citizen of the United States, and resident of Milwaukee, in the county of Milwaukee and State of Wisconsin, have invented certain new and useful Improvements in Attachments for Tables and other Supports; and I do hereby declare that the following is a full, clear, and exact description thereof.

10 My invention consists in what is herein particularly set forth with reference to the accompanying drawings and pointed out in the claims of this specification, its object being to provide tables or other supports 15 with simple, economical and efficient swing-tray attachments for holding smokers' refuse and with trays upon which to stand beverage glasses. The attachments are each preferably provided with a clip by which to 20 conveniently secure a carton of matches thereto, and said attachments are especially designed for tables on which games of cards, chess, checkers, dominoes, etc., are played.

Figure 1 of the drawings represents a sectional view of a fragment of a table and one 25 of my improved attachments therewith, the attachment being extended and the view indicated by line 1—1 in the next described showing; Fig. 2, a plan view of the extended attachment partly broken away and 30 the fragment of table in horizontal section, the view being indicated by line 2—2 in Fig. 1; and Fig. 3, a similar view illustrating 35 said attachment contracted and swung in out of the way.

Referring by numerals to Figs. 1, 2 and 40 3 of the drawings, 4 indicates the top of a table and 5 a frame-strip under the same. The frame-strip is provided with a clearance-slot 6, longitudinally thereof through 45 which to swing the attachment herein specified, and communicating with the slot is an upper recess 7 in said strip. Held by a pivot 8 in said recess on a wear-plate 9 is a shank 50 extension 10' of the centrally open flat top 10 of a circular cage having a flat bottom 11, the top being provided with a radial slot in communication with its central opening. Bars of the cage are sleeves 12 on pins 55 13, the pins being upset at their ends in the top and bottom of said cage. Another pin 13' is made to serve as a pivot for the shank 14' of a countersunk ring 14 in which to seat

a removable tray 15, said shank being supported on a spacing-block 16 on the cage- 55 bottom.

Depending from the underside of the cage-bottom 11 is an angular clip 17 by which to support a carton 18 of matches. The clip herein shown is a double right-angle strip 60 of otherwise flat spring-metal its flange 17' being fastened by a screw 19 to the cage-bottom and its vertical portion provided with a finger aperture through which to push out the drawer of the match carton. 65 Prongs are struck up from the horizontal lower portion of said clip to embed themselves in the drawer-casing of said carton, one of the prongs 20 being shown in Fig. 1.

The pivotal cage and parts therewith constitute a table attachment in accordance with 70 my invention, the same being contracted by swinging the ring 14 and tray therewith into said cage so that the whole assemblage may be swung in under the top of the table to 75 which it is connected, this contraction and out of the way position of said attachment being shown by Fig. 3.

In Figs. 1 and 2, the above described attachment is shown as it appears swung out 80 from under the table-top and extended by swinging the ring and tray therewith out of the cage, the clip for the match carton being so disposed in connection with the underside of the bottom of said cage as to be convenient to a person seated at the table. The tray 15 serves as a holder for the refuse of a smoker, and the cage, clear of said tray or stand and the ring therefor serves also as a tray upon which to support a goblet or other 90 beverage glass. The slot in the cage-top affords clearance for the stem of a goblet and the central opening in said cage-top has the same function for a tumbler form of beverage glass. 95

Without departure from the scope of my invention, as herein claimed, the detail thereof may be varied in practice, and an attachment in accordance with my invention may have pivotal suspension from a shelf, wall-bracket or other support the same as from the table-top herein specified.

I claim:

1. A tray in the form of a cage for pivotal connection with a support and which 105 has a centrally open radially slotted top, to

gether with another tray having pivotal support in connection with the cage to be swung in and out of the same.

2. A tray in the form of a stand for pivotal connection with a support, a ring in pivotal connection with the stand to be swung in and out of register with the same, and a removable tray for which the ring constitutes a seat.

In testimony that I claim the foregoing ¹⁰ I have hereunto set my hand at Milwaukee in the county of Milwaukee and State of Wisconsin in the presence of two witnesses.

EDWARD L. COMBES.
